UNITED STATES PATENT OFFICE.

THOMAS C. FRADSHAM, OF CARSON CITY, NEVADA.

TYPEWRITING-MACHINE.

1,383,166.

Specification of Letters Patent.

Patented Mar. 9, 1920.

Application filed November 22, 1917, Serial No. 203,419. Renewed January 26, 1920. Serial No. 354,248.

To all whom it may concern:

Be it known that I, THOMAS C. FRADSHAM, a citizen of the United States, residing at Carson City, in the county of Ormsby, State of Nevada, have invented certain new and useful Improvements in Typewriting-Machines; and I do hereby declare the following to be a full, clear, and exact description of the invention, such as will enable others skilled in the art to which it appertains to make and use the same.

This invention is an improvement in typewriting machines and has particular reference to a signaling attachment therefor.

An object of the invention is to provide an improved attachment which, when mounted in position on a typewriting machine, will indicate, at a predetermined point, that the lines are approaching the end of the page thus enabling the operator to accurately terminate the last line of typewriting the desired distance from the bottom of the page.

Another object is to provide an attachment of this character which is simple in construction, easy to manufacture, readily attached to machines of different type and effective in carrying out the purpose for which it is designed.

The inventive idea involved is capable of receiving a variety of mechanical expressions one of which, for the purpose of illustrating the invention, is shown in the accompanying drawing wherein:

Fig. 1 is a fragmentary plan view of the carriage of a typewriting machine showing the invention applied thereto.

Fig. 2 is a section taken on the line 2—2 of Fig. 1 showing parts of the attachment in their positions previous to being actuated.

Fig. 3 is a view similar to Fig. 2 showing parts of the attachment in their positions just previous to the operation of the signals.

Fig. 4 is a section on the line 4—4 of Fig. 2.

Fig. 5 is a detail perspective view of the striker arm and trip member carried thereby.

Referring more particularly to the drawing the numeral 5 indicates conventionally the carriage of a typewriting machine of known construction having the usual platen 6 mounted therein and provided with a shaft 7 having a turning knob 8 upon the end thereof.

The attachment which comprises the essential feature of the invention preferably

consists of a bracket 9 secured to the end of the carriage 5 in any suitable manner and supporting the small bell 10 with which is associated a striker 11 including a resilient arm secured at one end to the carriage 5 as indicated at 12.

A large gear 13 is preferably mounted upon a screw 14 or other pivot secured to the adjacent end of the carriage 5 and said gear is provided with a dial face having a plurality of apertures 15 adjacent the periphery thereof and said apertures are numbered and the distance between adjacent apertures designed to indicate one inch of the length of a sheet of paper. An adjustable spring arm 16 has one end mounted upon the screw 14 and is movable around the dial to any desired position, said arm carrying at its outer end, a locking pin 17 adjustable into engagement with any one of the apertures or openings 15 so as to releasably retain the arm 16 in an adjusted position.

The striker arm 11 preferably carries a lug 18 adjacent its secured end and said lug has a projecting shoulder 19 thereon which engages in a recess 20 formed in a trip arm 21 when the same is in normal position, said arm being pivoted to the lug 18 at 22 and having a beveled end 23 the under side of which is adapted to be engaged by the enlarged head 24 of the pin 17 at a predetermined time to bodily move said trip and striker away from the bell 10 and then release said parts to permit the striker to engage the bell. This action occurs when the gear 13 is rotated in a counter clockwise direction as is usual when the typewriter is being operated, but should the gear be turned in the opposite direction, as when turning the paper backward the head 24 may eventually engage the beveled surface of the end 23 and thus rock the trip 21 independently of the striker and thus permit the head to pass the trip without sounding the signal, the trip being then returned to its normal position by means of a small counter weight 25 formed upon the outer end thereof.

The gear 13 is operated by means of a similar gear 26 mounted upon the shaft 7 of the platen 6 and it will thus be seen that said gear 13 will be rotated each time the platen is turned during the progress of writing upon a sheet of paper.

In practice, should a sheet of paper or page ten inches long be inserted into the machine and written upon and should it be

desired to terminate the writing one inch from the bottom of the page, the pin 17 is disengaged from the gear 13 and the spring arm 16 is then rotated until said pin 17 is 5 in registration with the aperture numbered 9 whereupon said pin is engaged with said aperture so that the arm 16 will move with the gear as the same is rotated. Before placing the paper in the carriage, however, 10 the dial is turned until the arm 16 is adjacent the upper edge of the trip 21. It will thus be apparent that as the gear 13 is rotated the arm 16 will approach and finally engage the lower edge of the trip 21 and 15 move the same and the striker 11 outwardly and upon further movement of said arm the trip will be disengaged and the striker released to strike the bell 10. In this manner the operator will be informed that the 20 last line of typewriting is at the desired distance from the bottom of the page.

What is claimed is:—

1. The combination with a typewriter platen of a disk rotatable therefrom, a 25 striker adjustable rotatably of the disk, a bell, a spring clapper for the bell fixed at one end and a strip carried by the clap-

per in the path of movement of the striker and operable by movement of the striker in one direction only, to retract and subsequently release the clapper, the trip having lost motion with respect to the clapper under the influence of movement of the striker in the opposite direction. 30

2. In a typewriter, the combination with 35 a movable platen, of a striker rotatable from the platen and adjustable in the direction of its rotation, a bell, a spring clapper for the bell normally out of contact therewith, a trip pivotally connected with the clapper, 40 and gravity actuated means for holding the trip normally in the path of movement of the striker, the trip being operable to actuate the clapper by and in one direction of movement of the striker and having lost motion with respect to the clapper under the influence of movement of the striker in the opposite direction. 45

In testimony whereof, I affix my signature in the presence of two witnesses.

THOMAS C. FRADSHAM.
